UNITED STATES PATENT OFFICE.

JOSEPH RADÓ, OF CLEVELAND, OHIO.

INDICATING ELECTRIC SWITCH.

1,221,590.

Specification of Letters Patent. Patented Apr. 3, 1917.

Application filed March 4, 1915, Serial No. 12,135. Renewed January 11, 1917. Serial No. 141,915.

To all whom it may concern:

Be it known that I, JOSEPH RADÓ, a subject of the King of Hungary, residing at Cleveland, in the county of Cuyahoga and State of Ohio, have invented certain new and useful Improvements in Indicating Electric Switches, of which the following is a specification.

My invention relates to electric switches and particularly to the manner of automatically indicating the location of said switches.

Under ordinary conditions when it is desired to turn on the lights in a darkened room it is necessary to grope around in order to find the switch for controlling the illumination of the room.

With my invention I provide a pilot lamp or signal in association with the switch which is automatically caused to light when the room becomes darkened. The pilot lamp is preferably lighted from the same current which supplies the lamps used for illuminating purposes. The pilot lamp is of low voltage as compared with the illuminating lamps and when the same source of current is used for both, then a suitable form of resistance is placed in series with the pilot lamp. In addition to the pilot lamp I provide a selenium cell which is connected in multiple with the pilot lamp.

Selenium cells have the characteristic of lowering their resistance when exposed to the light and of increasing their resistance when placed in darkness. The resistance of the cell when exposed to the light and when placed in multiple with the pilot lamp shunts a greater portion of the current flowing through the resistance coil and so prevents the pilot lamp from lighting. When, however, the room becomes darkened, the resistance of the selenium cell increases, thereby allowing more current to flow through the pilot lamp and causing its illumination.

While I have shown my invention as applied to switches of the push button type, it naturally follows that switches of other types may be employed. When switches of the former type are used I prefer to mount the pilot lamp within one of the push buttons as illustrated in the drawings.

My invention is illustrated in the accompanying drawings, wherein:

Figure 1 is a plan view of the push button switch containing a pilot lamp.

Fig. 2 is a section showing the construction of the push button in which the pilot lamp is mounted.

Fig. 3 is a plan view of a two-button switch with a portion of the front plate cut away.

Fig. 4 is a side view of a two-button switch partly in section.

Fig. 5 is a diagram showing the circuit connections.

Fig. 2 plainly shows the method of mounting the lamp within the push button. In order to remove the lamp the portion 1 of the button is turned as it is threaded into the portion 24 which carries the lamp base 70 and its connections. The selenium cell 6 is also mounted or embedded in the portion 24 of push button. After the portion 1 of the button is removed the bulb 2 is rendered accessible. This bulb is turned in order to remove it from the portion 24 with which its base is threaded.

The connections for the lamp terminate in the lugs or ears 4 and 8. When the button containing the lamp is in its non-depressed position these lugs or ears complete the circuit connections for the lamp as plainly indicated in Figs. 3, 4 and 5.

Figs. 2 and 5 plainly show the manner in which the selenium cell 6 is connected in multiple with the terminals of the lamp 2. The shell or cap 1 of the push button is provided with a transparent window 3 through which the light is reflected by the lamp 2.

Figs. 3 and 4 show details of the ordinary push-button type switch to which I have applied my invention. When the buttons are in the position shown in Fig. 4, the circuit which controls the lamps used for illuminating purposes is broken. When, however, the lower button containing the pilot lamp is depressed the circuit is closed by the end 15 of the conducting segment A engaging the terminal 14 and the end 12 engaging the terminal 13. This segment A is pivoted at 25 and serves to open or close the circuit, depending upon which button is depressed.

When the button is depressed for closing the circuit for the illuminating lamps the lugs or ears 4 and 8 break the circuit connection extending to the pilot lamp 2. The circuit conditions are plainly shown in Fig. 5. G represents a generator or source of current for lighting the lamps. 10 is a resistance coil in series with the pilot lamp 110.

2 which is in multiple with the selenium cell 6. 50 is a lamp used for illuminating purposes and, of course, any number of these lamps may be used.

5 When the pilot lamp button is in its non-depressed position, as shown, the circuit for the lamp 2 is closed by the following path:

Generator G to the contact lug 4, conductor 5, lamp 2, contact lug 8, resistance 10 coil 10 to the opposite side of the generator G.

We will assume that the room in which the switch containing the pilot lamp is lighted; under such conditions the resistance of 15 the selenium cell 6 will be such that a greater portion of the current which passes through the resistance 10 by way of the circuit just traced will pass through the cell 6, thereby preventing the lighting of the lamp 2.

20 When, however, the room becomes darkened the resistance of the cell 6 increases thereby allowing enough current to flow by way of the path previously traced to pass through the lamp 2 causing it to light. The lighting 25 of this lamp plainly indicates the position of the switch or button. When it is desired to turn on the lights in the room, the button containing the lamp is depressed thereby causing the portion 15 of segment 30 A to engage the terminal 14 and the portion 12 to engage the terminal 13 thereby completing the circuit for the illuminating lamp 50.

The depression of this button which causes 35 the lighting of the lamp 50 also causes the circuit connections to the lamp 2 to be broken thereby extinguishing it.

My invention is particularly applicable when used in conjunction with a group of 40 push buttons. In apartment houses it is customary to place a group of push buttons for signaling purposes in the vestibule and designate such buttons by number. With my invention when the lamp is mounted 45 within the button, the window or opening of the button can be provided with a suitable number which is illuminated by the pilot lamp when the vestibule becomes darkened.

50 Having thus described my invention, what I desire to secure by Letters Patent is:

1. The combination with an electric switch, of an illuminating lamp controlled by said switch, a pilot lamp illuminating 55 said switch, means comprising a selenium cell associated with said switch for automatically causing said pilot lamp to light when said illuminating lamp is extinguished, additional means for causing said pilot lamp 60 to be extinguished when said illuminating lamp is lighted.

2. The combination with an electric switch, of an illuminating lamp controlled by said switch, a push button actuating said 65 switch containing a pilot lamp, means com-

prising a selenium cell associated with said switch for automatically causing said pilot lamp to light when said illuminating lamp is extinguished, additional means for causing said pilot lamp to be extinguished when 70 said illuminating lamp is lighted.

3. The combination with an electric switch, of a push button actuating said switch, a pilot lamp mounted within said push button, automatic means comprising 75 a selenium cell for causing said lamp to light when said push button is in its normal position, additional means for causing said lamp to become extinguished when said push button is depressed.

4. The combination with an electric switch, of a push button actuating said switch, of a pilot lamp mounted within said button, of means comprising a selenium cell for controlling the illumination of said lamp, of means controlled by said push button for in turn controlling the action of said selenium cell.

5. The combination with an electric switch, of a pilot lamp associated with and 80 for indicating the location of said switch, means for illuminating said lamp, means comprising a selenium cell for controlling the illuminating of the pilot lamp, additional means for preventing the illumination 85 of said lamp.

6. The combination with an electric switch, of a pilot lamp associated with and 90 for indicating the position of said switch, means for illuminating said lamp, a selenium cell connected in multiple with said lamp for regulating the illumination of said lamp.

7. The combination with an electric switch, of a push button actuating said 95 switch, of a pilot lamp, a selenium cell connected in multiple with said lamp, said cell controlling the illumination of said lamp, means controlled by said button for controlling the action of said selenium cell.

8. The combination with a switch, of a push button actuating said switch, a pilot lamp mounted within said button, controlling means comprising a selenium cell also mounted within said button for determining 115 whether said lamp shall be lighted or extinguished.

9. The combination with a switch, of a button actuating said switch, a pilot lamp mounted within said button, of means comprising 120 a selenium cell also mounted within said button for controlling the illumination of said lamp, of means controlled by said button for in turn controlling the action of said selenium cell.

10. The combination with a switch, of an illuminating lamp controlled by said switch, a button associated with said switch and containing a pilot lamp, automatic means 125 for causing said pilot lamp to be lighted.

when said illuminating lamp is extinguished, manual means for causing said pilot lamp to be extinguished when said illuminating lamp is lighted.

5 11. The combination with a switch, of a button actuating said switch, a pilot lamp, means comprising a selenium cell for controlling the lighting of said lamp, means

controlled by said button for extinguishing said lamp. 10

In testimony whereof I affix my signature in presence of two witnesses.

JOSEPH RADO.
